SOCKET WRENCH

Filed Feb. 5, 1932

John Greiner INVENTOR
BY Victor J. Evans & CO ATTORNEYS

UNITED STATES PATENT OFFICE

JOHN GREINER, OF PHILADELPHIA, PENNSYLVANIA

SOCKET WRENCH

Application filed February 5, 1932. Serial No. 591,189.

The invention relates to an improved socket wrench, and the purpose of the invention is to provide a holding shell for the reception of a plurality of interior nut engaging socket tubes, which are yieldably mounted individually in the shell, so that the innermost nut engaging socket tube may engage one size of nut or bolt head and then when the wrench is applied for use on a larger nut, the innermost socket tube can be receded, and when a larger size of nut is engaged the innermost and the next size nut engaging socket tube may be receded. This operation may be carried out for various sizes of nuts or bolt heads.

Another purpose is to provide a socket wrench of this kind wherein the plurality of nut engaging socket tubes are of substantial length, and the innermost nut engaging socket tube is interiorly unobstructed, so that bolts of considerable length can extend into the various tubes and yet not interfere with the removal of the nut. This arrangement is one of the particular features of the invention.

A further and a most important purpose is to construct the nested socket engaging tubes, each of a plurality of strips arranged in polygonal relation so as to provide polygonal shape to the tubes, the inner ends of the strips being inclined and provided with openings to receive clamped ears, of correspondingly inclined arms of several ring members, to provide seats with which the springs engage to hold the tubes in position and allow them to yield, the springs being in turn engaged within flanges on a head, in order to retain the springs in position, whereby each individual nut engaging socket tube may yield automatically and individually.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter

set forth, shown in the drawing and claimed.

In the drawing:—

Figure 1 is a view in perspective of the improved socket wrench constructed in accordance with the invention.

Figure 2 is a longitudinal sectional view through the same.

Figure 3 is a cross sectional view on line 3—3 of Figure 2.

Figure 4 is a cross sectional view on line 4—4 of Figure 2.

Figure 5 is an enlarged detail view showing how one of the strips constituting one of the faces of any one of the polygonal socket engaging tubes is attached to a ring forming a seat for one of the springs.

Referring to the drawing 1 identifies an outer body shell, which comprises a large portion 2 and a smaller portion 3, that is to say portions larger and smaller in diameter it being obvious that these proportions as well as the length of said parts can be varied, according to the size of wrench to be constructed.

The larger portion or section 2 integrally joins the smaller portion or section 3 by means of an intermediate tapered section 4. A cap or cover 5 is threaded at 6 into the section 2 of the wrench shell body, for the purpose of retaining a plurality of springs in position.

The section 3 of the wrench shell body is polygonal in cross section, namely the cross sectional area may be made to fit a square nut, a hex nut or an eight sides nut.

Arranged in the section or portion 3 of the wrench shell body is a plurality of nut engaging socket tubes 9, 10, 11 and 12, though it is obvious that any number of inner tubes may be used. The inner tubes 9, 10 and 11 at portions adjacent the tapered section 4 of the outer shell are likewise tapered as shown at 13, parts of which cooperate with each other for the purpose of limiting the inner nut engaging socket tubes in their normal positions with their marginal end edges 14 flush.

Each of the nut engaging socket tubes, excepting the outer shell is made up of a plurality of metallic strips, in the form of steel

blades, 15, which are arranged in polygonal formation, in order to form correspondingly shaped socket tubes. The inner ends of the strips or blades have inclined extensions corresponding to the taper of the tapered section 4 of the outer shell. These inclined ends 16 have slots 17, through which tongues 18 engage for connecting correspondingly inclined extensions 19 of the rings 20 to the strips or blades. The rings are so arranged as to abut in order to limit the nut engaging socket tubes with their edges 14 flush. The rings 20 have flanges 21, within which coil springs 22 engage. The springs 22 in turn engage within flanges 23 carried by the cap or head 5, thereby retaining the springs in position, so that the nut engaging socket tubes may yield, according to the one or those which are receded.

Obviously by permitting a hex nut to engage the innermost nut engaging socket tube 12, the shank of the bolt may extend into the tube for a substantial distance. In case it is desired that a larger hex nut may engage 25 within the nut engaging socket tube 10, the tubes 11 and 12 may be receded. By grasping the larger section of the wrench shell body, it is possible to rotate the wrench in either direction by hand.

The invention having been set forth, what is claimed is:

1. In a socket wrench, the combination with an outer wrench body shell having a contracted nut engaging socket section of elongated formation and a tubular handle section of larger diameter than the first section and an intermediate tapered section integrally connecting the first two sections, of a plurality of telescopically united nut engaging socket tubes telescopically mounted in the first section of the shell, a head for the handle section, said plurality of nut engaging socket tubes having extension arms, flanged rings of gradual increasing diameters located at one end of the handle section and having arms connected to the arms of the nut engaging socket tubes, said flange rings being abutted and the flanged ring of larger diameter engaging a shoulder where the tapered section merges into the handle section, thereby limiting the nut engaging socket tubes with their outer end edges flush, and spring means interposed between the flanged rings and the head, thereby yieldably mounting the nut engaging socket tubes.

2. In a socket wrench, an outer wrench body shell having a contracted nut engaging socket section of elongated formation and a tubular handle section of larger diameter than the first section, the first section being polygonal in cross sectional area, an intermediate tapered part joining the two sections, a plurality of telescopically united nut engaging socket tubes corresponding in cross sectional area to and mounted in the poly-

gonal shape section, a head for the handle section, the inner ends of the nut engaging socket tubes having inclined extension arms conforming to the intermediate tapered section of the shell, a plurality of abutting flanged rings of gradual increasing diameters with the ring of larger diameter abutting a shoulder where the tapered section merges into the handle section, said rings provided with extension arms conforming to and engaging the arms of the nut engaging socket tubes, slot and lug connections uniting the arms, the abutting of the flanged rings acting to limit the tubes with their outer ends flush, and yieldable means between the flanged rings and the head.

3. A socket wrench, consisting of an outer wrench body shell having a contracted nut engaging socket section of elongated formation polygonal in cross sectional area, and a tubular handle section of larger diameter than the first section, said body shell also having an intermediate tapered section uniting the first two sections, a head for the handle section, a plurality of telescopically united nut engaging socket tubes corresponding in cross sectional area to and nested within the polygonal section of the shell, said nut engaging socket tubes being made up from a plurality of strips or blades constituting the polygonal sides of the tubes, the inner ends of the blades having inclined extension arms corresponding to the intermediate tapered section, a plurality of rings adjacent the intermediate tapered section and provided with extension arms positioned to correspond to the intermediate tapered section and engaging against the first arms, means for uniting both sets of arms, and yieldable means interposed between the rings and the head for yieldably supporting the nested nut engaging socket tubes.

In testimony whereof I affix my signature.
JOHN GREINER.
